UNITED STATES PATENT OFFICE.

SOLOMON KLEPFER, OF INDIANAPOLIS, INDIANA.

METAL CARD.

Application filed September 22, 1926. Serial No. 137,055.

This invention aims to provide a novel division plate for a filing cabinet, the division plate being so constructed that it can be moved forwardly or backwardly, and not carry with it, the slips of paper which are between it and another division plate.

Another object of the invention is to provide novel means whereby the division plate may be handled readily and may be mounted 10 in a cabinet.

It is within the province of the disclosure to improve generally and to enhance the utility of devices of that type to which the invention appertains.

15 With the above and other objects in view which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 In the drawings:—

Figure 1 shows in elevation, a device constructed in accordance with the invention, a part of the cabinet appearing in section;

Figure 2 is a side elevation.

30 The plate 1 is made of any desired material, but metal is preferred, and a light metal, such as aluminum, may be used. The plate 1 is of rectangular contour and is provided at its lower end with a depending finger 2, located about midway between the side edges 3 and 4 of the plate. The finger 2 has an opening 5. The finger 2 is adapted 35 to extend downwardly into a slot 6 that is formed in the bottom 7 of the filing cabinet.

40 The filing cabinet may be supplied with a rod 8 or other retainer, which, passing through the opening 5, holds the division plate in place in the cabinet, without, however, preventing the plate from being tilted

45 forwardly or backwardly, as occasion may demand. For the purposes of identification or classification, and to facilitate the movement of the division plate, the same is sup-

plied on its upper edge 9 with an upstanding tab 10 which may carry a numeral or 50 other identifying mark, as at 11. The tab 10 may be located anywhere between the edges 3 and 4 of the plate. Near to its upper edge 9, the plate 1 has a plurality of openings 12 which, preferably, are in the 55 form of slots, elongated in the direction of the length of the plate 1 and spaced apart transversely of the plate.

In practical operation, a number of the plates 1 are used together, in the cabinet, as 60 indicated in Figure 2, and leaves or papers, shown at 14, are disposed between the plates. When any ordinary plate is slipped forwardly from the solid line position of Figure 2, to the dotted line position of that figure, the plate tends to carry with it, at least one of the leaves 14 which is immediately adjacent to the said plate, and, often, other leaves are carried along in the same way, also. In the device forming the subject 70 matter of this application, the plate 1 may be swung forward and will not carry the slip or leaf of paper along with it. This is true because the plate is provided near to its upper edge with the openings 12 which admit 75 air on the upper part of the leaf and prevent the leaf from swinging forwardly along with the plate.

What is claimed is:—

A device of the class described embodying a division plate adapted to be used between thin slips in a filing and indexing mechanism, the plate being stiff enough so that it can be tilted without bending, the plate being provided near to its upper edge 80 with a plurality of transversely spaced openings which are elongated perpendicularly to said edge sufficiently to admit air on the imperforate portion of the slip next adjoining the plate, thereby to prevent the slips from 85 being carried along with the plate when the plate is tilted as aforesaid.

In testimony that I claim the foregoing as my own, I have hereto affixed my signature.

SOLOMON KLEPFER.
